US0D1025930S

(12) **United States Design Patent** (10) Patent No.: **US D1,025,930 S**
(45) Date of Patent: ** May 7, 2024

(54) **CONTROLLER**

(71) Applicant: **eMoMo Technology Co., Ltd.**, Shenzhen (CN)

(72) Inventors: **Wei Zhou**, Wuhan (CN); **Wenji Tang**, Shenzhen (CN); **Jing Song**, Shenzhen (CN); **Yushu Zhao**, Shenzhen (CN); **Xiaolian Zhou**, Shenzhen (CN); **Zhigang Wang**, Qiyang (CN); **Jun Yang**, Shenzhen (CN); **Qishuang Lu**, Dengzhou (CN); **Juntao Chen**, Shenzhen (CN); **Yi Wang**, Wuhan (CN)

(73) Assignee: **EMOMO TECHNOLOGY CO., LTD.**, Shenzhen (CN)

(**) Term: **15 Years**

(21) Appl. No.: **29/868,155**

(22) Filed: **Nov. 22, 2022**

(30) **Foreign Application Priority Data**

May 23, 2022 (CN) 202230306514.5

(57) **CLAIM**

We claim the ornamental design of a controller, as shown and described.

DESCRIPTION

FIG. 1 is a bottom, left, rear perspective view of a controller showing an embodiment of our new design;

FIG. 2 is a top plan view of the controller of FIG. 1;

FIG. 3 is a bottom plan view of the controller of FIG. 1;

FIG. 4 is a front elevated view of the controller of FIG. 1;

FIG. 5 is a rear elevated view of the controller of FIG. 1;

FIG. 6 is a left-side elevated view of the controller of FIG. 1; and,

FIG. 7 is a right-side elevated view of the controller of FIG. 1.

1 Claim, 7 Drawing Sheets
